UNITED STATES PATENT OFFICE.

JAMES H. BERKOVEC, OF CHICAGO, ILLINOIS.

MOP-HEAD.

1,280,135.

Specification of Letters Patent.

Patented Oct. 1, 1918.

Application filed December 1, 1916. Serial No. 134,258.

To all whom it may concern:

Be it known that I, JAMES H. BERKOVEC, a citizen of the United States, and resident of Chicago, in the county of Cook and State 5 of Illinois, have invented certain new and useful Improvements in Mop-Heads, of which the following is a full, clear, and exact specification.

This invention relates to improvements in 10 mop heads heretofore consisting of a continuous frame, bent from a single piece of interlocked wire, terminating at one end in a convolute forming a socket for removably securing the mop stick or handle thereto in 15 its operative position, the mop for which consists of fibrous strands looped at their middle over and upon the frame, and stitched between the fold of a flexible woven fabric so loosely surrounding and 20 free to turn and twist on the frame that in operation the fibrous strands are forced upwardly into a matted mass, locked to the frame, with the result that the effectiveness of the mop is accordingly reduced.

25 As the construction of mop heads from wires above described is desirable not only for cheapness of construction, lightness and durability, but that they yield under pressure, require less exertion and concentrated 30 force for the operation of the mop, it is at once apparent that any means by which it is possible and practical for increasing the effectiveness of the fibrous strands will be a substantial and material improvement in 35 the mop art.

The prime object of my invention broadly stated is to provide the wire frame of a mop with means operating to maintain the fibrous strands in substantially an outstretched position, prevent their matting and permanent retention within the confines of the frame, and thereby accordingly promote the effectiveness and usefulness of the 40 mop.

45 More specifically stated the object of my invention is a mop head consisting of a wire frame provided with means for shifting the bending point of the fibrous strands in a plane below that occupied by the frame.

50 Another object of my invention is to provide a means for shifting the bending point of the fibrous strands as above stated, and which is adapted to provide a locking means for the free end of the wire of the frame 55 and furthermore if desired a yielding sup-

port for the base of the convolute forming the socket for the handle.

With these ends in view, my invention finds embodiment in certain features of novelty in the construction, combination and arrangement of parts by which the said objects and certain other objects are attained, all as hereinafter fully described with reference to the accompanying drawings, and more particularly pointed out in the claims. 65

In said drawing:

Figure 1 illustrates a top plan view of a mop head and mop therefor, in which my invention finds its embodiment.

Fig. 2 is a fragmentary detail showing 70 the means for shifting the bending point of the fibrous strands below, outwardly from the plane of the frame and its adaptability to form a fastening for the free end of the wire of the frame, and a support for the 75 convolute forming the socket portion therefor, and—

Fig. 3 is a vertical section taken on the line 3—3 of Fig. 2.

Similar characters of reference indicate 80 the same parts in the several figures of the drawing.

The wire frame 4, the construction of the 85 mop 5, the convolute 6 forming a socket for the handle 7, and the bending of the free end 8 around a portion of the frame to make it continuous, are of the usual form and construction heretofore employed, as is also the looping of the fibrous strands 9 over the frame at their middle, and securing them 90 together by means of stitches 10 passing therethrough, and through a woven fabric 11 looped over the frame, and between the folds of which the fibrous strands are projected. 95

Projecting from the frame 4 is a flange 12 which may be of any suitable material, as for example bars of bent wood sleeved on the frame, but preferably consists of a continuous strip of resilient sheet metal, the 100 depending ends of which are brought together after being bent about the frame as indicated at 13, of a thickness and stiffness best adapted for the purposes of its use, and which owing to the bends therein conforming to the frame is fixed in its operative position so that the edge of the flange will determine the bending point of the fibrous strands, and which as indicated in the drawing is substantially below the plane of the 110

frame 4, and such a distance that the longest strands may be used consistent with preventing their free ends from permanently remaining and matting within the frame 5 during the operation of the mop, owing to the fact that the stitches 10 are secured adjacent the edge of the flange.

One end 14 of the flange terminates at a point slightly removed from the coils forming the handle socket, the other end 15 of which, however, preferably projects across the end of the convolute sufficiently to provide a seat for the convolute. To prevent the two members of the flange from spreading 15 apart, they may be riveted together, but in practice their corners 16—16 are bent together over upon one of the surfaces of the flange, as shown in Fig. 2.

The end 15 of the flange may also be provided with a perforation 17 forming a lock 20 for and through which to project the end of the bend in the frame, which is thereby made continuous and a rigid structure, especially when supplemented by the flange 25 when formed as shown in Fig. 3.

As a further means for supporting the convolute, the free end of the frame is projected between coils near the bottom thereof as indicated at 18, but both this and the locking of the free end of the frame to the flange through the provision of a perforation therein are features which may be dispensed with without a substantial departure 30 from my invention, the essential feature of 35 which resides in a flange secured in a fixed and non-rotatable position to and depending below the wire frame of a mop head, whereby the bending point of the fibrous strands of a mop mounted thereon is low-

ered below the plane of the frame to a distance sufficient to prevent the free ends of the fibrous strands of the mop from projecting upwardly and matting within the frame, and whereby they are maintained in a substantially outstretched and operative position 45 throughout the operation of the mop.

Having described my invention, what I claim and desire to secure by Letters Patent is:

1. A mop head, having a continuous 50 frame, formed from a single piece of wire, a mop mounted thereon, and a substantially rigid strip suspended from the frame for shifting the bending point to the fibrous strands of the mop to a plane substantially 55 below the plane of said frame.

2. A mop head, having a continuous frame formed from a single piece of wire, a mop surrounding said frame, a metal flange suspended from the frame for shifting the 60 bending point of the fibrous strands of the mop to a plane substantially below the plane of said frame.

3. A mop head, the frame of which is formed from a continuous piece of wire, a 65 convolute for the handle continuous with said wire, a mop surrounding said frame, and depending below the same, a flange projecting below the frame, consisting of sheet metal surrounding and secured to the frame. 70

In witness whereof, I have hereunto set my hand and affixed my seal, this 25th day of November, A. D. 1916.

JAMES H. BERKOVEC. [L. S.]
